UNITED STATES PATENT OFFICE.

CHARLES A. WENBORNE, OF CHICAGO, ILLINOIS.

KILN.

No. 918,621.

Specification of Letters Patent. Patented April 20, 1909.

Application filed December 2, 1908. Serial No. 465,612.

To all whom it may concern:

Be it known that I, CHARLES A. WENBORNE, a citizen of the United States of America, and a resident of Chicago, county of Cook, State of Illinois, have invented certain new and useful Improvements in Kilns, of which the following is a specification.

The main objects of this invention are to provide an improved form of drying kiln; to provide a kiln particularly adapted for accelerating the drying of coatings of oil, paint, varnish, shellac, and kindred substances after they have been applied to articles of wood or other materials for the purpose of filling the pores or giving an artificial surface to the articles; to provide a kiln of this class in which means are provided for effectually preventing the contamination of the surfaces of the coatings during the period of solidification, as by dust, soot, or other impurities floating in the air; to provide improved means whereby such coatings may be solidified in such manner as to give greater stability thereto and greater capacity to resist extraordinary temperatures than such surfaces have when solidified by mere exposure to the air at ordinary temperatures; to provide improved apparatus for rapidly drying articles and substances that will not withstand the application of temperatures much above ordinary temperatures, as, for instance, glue, tobacco, and candy; and to provide an improved form of kiln which is capable of varied operation so as to dry a great variety of different substances, regardless of whether the drying depends upon the evaporation of moisture or volatile liquids, or upon oxidation or other effects of exposure to the air or a gas or vapor. These objects are accomplished by the device shown in the accompanying drawings, in which:

Figure 1 is a diagrammatic longitudinal section of a drying kiln embodying this invention. Fig. 2 is a side elevation of the same, partly broken away. Fig. 3 illustrates a modified form of the kiln in which the heating coils 7 are omitted. Fig. 4 is an end elevation of a modified form of support suitable for use when the articles to be treated are of such form that they must be suspended from above.

In the form shown in the drawings, the kiln comprises a room or series of rooms

having walls suitably insulated to prevent the loss of heat, and any openings in the walls are provided with doors or closures which are sufficiently tight to prevent the efflux or influx of air except when it is desired, as hereinafter explained.

The main body of the room forms a storage compartment A, within which are placed the articles which are to be treated. Comparatively narrow chambers B are cut off from the chamber A by means of vertical partitions 1. These partitions extend throughout the length of the room, but their upper and lower edges are spaced away from the ceiling and floor of the room so as to provide air outlet and inlet passages 3 and 4. The chambers A and B and the passages 3 and 4 are coextensive with each other lengthwise of the kiln. A horizontal support 5 is provided for supporting the articles to be treated in the chamber. The support 5 is spaced above the floor so as to allow room for the free passage of air under it. The support 5 may be provided with tracks so as to permit the articles to be brought into the room on cars, and should be so constructed as to offer as little resistance as possible to the upward flow of air through the chamber A.

A series of heating coils 6 extend across the room at a considerable distance below the ceiling, but at such height above the support 5 as to provide the desired amount of head room in the storage space below. There is also a series of heating coils 7 located immediately below the support 5. The coils 6 and 7 extend from end to end of the chamber A, so that the heating effect is uniformly distributed throughout the entire horizontal area of the chamber A.

In order to prevent the direct radiation of heat from the coils 6 to the articles in the chamber A, means are provided for reflecting the heat rays without interfering with the free flow of air. This is preferably accomplished by means of a screen 8 spaced a short distance below the heating coils 6 and formed of a series of parallel angle bars or deflectors so located with respect to each other as to allow free passage of air between them and at the same time prevent the direct heat rays from getting through.

Each of the chambers B has a coil 9 in its upper part. These coils are so arranged as

to cool the air in the upper part of the chambers B by means of a suitable cooling medium, as, for instance, cold water circulated through the coils. When two cooling chambers B are provided, it is preferred to subdivide the compartment C above the coils 6 by means of a vertical partition 10 which extends down from the ceiling to a point near the coils 6. A row of air outlets 11 is provided in the side wall of the room above the cooling coils 9, to permit the escape of heated air at that point when desired. These openings 11 are controlled by one or more sliding closures 12. A similar series of openings 13, provided with closures 14, extends along the chamber B immediately below the coils 9. Drip pans 15 are provided for catching any liquid which condenses and drops from the coils 9. These 20 are inclined and provided with a drain pipe at their lower end controlled by a pet-cock 16 (Fig. 2). Valves 17 control the flow of cooling medium in the coils 9, and valves 18 control the flow of heating medium in the 25 coils 6 and 7. The coils 6 and 7 should be separately controlled, so that either may be cut out at will or one may be regulated to a different temperature from that of the other, as will hereinafter appear. The coils 9 may 30 also be separately controlled to permit them to be regulated to relatively different temperatures.

In drying certain substances which contain volatile liquids, these are taken up by the air in its passage, and on account of the cooling of the conveying air at the coils 9, they are condensed upon said coils. In certain cases where the drying depends upon oxidation rather than the extracting of 40 moisture from the substance which is dried, it is desirable to add moisture to the air before it enters the air inlet 4. Any suitable means may be provided for this purpose. In the form shown, a trough 19 is 45 provided in the bottom of each of the compartments B, and there is also provided an inclined support 20 through which extend wicks 21 which dip into the trough 19 and soak up water therefrom. These wicks are 50 so located as to be in the path of the air entering the inlet 4. These troughs and wicks may also be used for adding certain other properties to the air. For instance, a liquid oxidizing agent may be fed to the 55 wicks and evaporated by the air and by it conveyed to the articles which are being dried. The effect of the wicks may be varied by exposing more or less of their surface to the air current. At times when no 60 moisture or vapor is being supplied to the air by the wicks, they may be covered by means of a hinged cover 22, operated from the outside by a handle 22'.

The outer walls 23 of the kiln are preferably made in sections which are hinged or

removable so as to permit of ready access to the coils 9, drip pans 15, and troughs 19. In the form shown in Fig. 2, the walls 23 are made in the form of a series of doors 24 in the vicinity of the coils 9. A door 25 is also 70 provided at the lower part of the walls 23. The remaining parts of said walls are secured by bolts, as there would seldom be occasion for removing them. The front and back of the kiln are closed by doors not 75 shown, which, when open, should provide an unobstructed passage into the drying chamber A.

The operation of the device shown is as follows:—The chamber A is loaded with the 80 articles which are to be dried, and the doors are then tightly closed. If the goods in the chamber A are of such nature that the drying depends upon oxidation or other chemical action, then steam is admitted to the 85 coils 6, but the coils 7 are shut off from the source of steam supply. The air around the coils 6 will expand and rise. Water or other fluid cooling medium is admitted into the coils 9, and the surrounding air is thus 90 cooled, becoming heavier and tending to fall. The combined effect of the coils is to cause a circulation in the direction of the arrows in Fig. 1. The velocity of the movement of the air depends upon the relative temperatures 95 in the heating and cooling coils and upon their respective distances below the ceiling and above the floor of the room, being, of course, due to the difference in weight of columns of air of equal horizontal area at 100 opposite sides of the partitions 1.

At the bottoms of the chambers B the air comes into contact with the wicks and takes up moisture therefrom, the wicks in turn drawing moisture from the troughs by capillary attraction. The moisture delivered depends upon the relative dryness of the air and the amount of wick surface exposed. These wicks are intended for use in cases where it is desired to insure a certain percentage of moisture in the air, so as to delay or prevent the evaporation of volatile ingredients of the substances, and also in cases where certain oxidizing or other agents are to be brought into contact with the substances treated. The wicks also equalize the moisture in the air of the kiln when the character or distribution of the goods causes differences in the dryness of the air at different parts of the kiln. When not in 115 use, the wicks are withdrawn from the air current or covered by the lids 22.

When the air enters the inlets 14, it spreads out over the bottom of the compartment D below the chamber A, and then rises 120 through the chamber A, again coming into contact with the steam coils, where it again becomes rarefied. If the steam in the coils 6 is kept at a uniform pressure, and if the flow of cooling medium in the coils 9 is also 125 130

kept constant, then there will be a continuous and uniformly regulated motion of the air which will flow in a circuit, its path being substantially at right angles to the sides 5 of the kiln on which the cooling chambers are located.

Inasmuch as the unequal heating of the chambers A by radiation from the heating coils is prevented by the screen 8, it is possible to apply the highest and most effective 10 temperature compatible with the chemical or physical properties of the materials which are being dried, without danger of injury to such materials. When drying certain 15 substances, the best results are obtained if the kiln is gradually cooled toward the end of the drying process. This may be accomplished by allowing some of the heated air to pass out of the openings 11 and admitting fresh air to the openings 13 to replace that which passes out at the openings 11. The openings 11 and 13 also serve to permit the replenishing of the air from time to time if the nature of the substance 20 being dried is such that the air loses its drying properties. The openings 13 are protected by dust-arresting fabric so as to prevent dust from entering with the air. The openings 11 and 13 may be opened periodically 25 or their closures may be adjusted so that a limited amount of air may escape and enter during the continuous operation of the kiln.

When the apparatus is used for evaporating 30 moisture or volatile liquids from the substances which are treated, then the heating coils 7 are put into service so as to heat the air and increase its evaporative power before it comes into contact with the goods 35 in the compartment A. The temperature of the coils 7 is regulated to an amount which the substances can withstand without injury, and the coils 6 are regulated to supply any desired amount of heat 40 to the air after it has passed from the chamber A, so as to insure the desired velocity of movement of the air. Thus the velocity of air current may be regulated to a desired amount quite independent of the temperature 45 within the drying compartment A, thus permitting of rapid drying at comparatively low temperatures.

If a certain kiln is to be used exclusively for the drying of certain substances which 50 do not contain moisture or volatile liquids, the coils 7 will be unnecessary and may be entirely omitted, as in Fig. 3. In such case the permanent support 5 would also be omitted or replaced by temporary movable 55 supports for holding the goods above the floor to permit air to circulate beneath. The form of such supports would be determined by the nature of the articles to be treated, for instance, they might be trucks of skeleton 60 construction, so as to offer minimum resist-

ance to the free circulation of air around the articles.

Suitable trucks for supporting articles of different character are shown at 26 and 27 70 in Figs. 3 and 4.

No attempt has been made herein to describe every possible specific construction within the scope of this invention and it will be understood that numerous details of the construction shown may be changed or omitted 75 without departing from the spirit of this invention.

I claim:

1. A kiln of the class described, comprising a drying chamber, a cooling chamber 80 located at one side of said drying chamber and communicating therewith at the top and bottom, heating coils extending horizontally across said drying chamber at a level above the middle of the height of said chamber, 85 and means for cooling the air in said cooling chamber, all being arranged to cause a circulation of air upwardly through said drying chamber and returning through said cooling chamber. 90

2. A kiln of the class described, comprising a drying chamber, a cooling chamber located at one side of said drying chamber and communicating therewith at the top and bottom, heating coils extending horizontally across said drying chamber at a level above the middle of the height of said chamber, and cooling coils located in said cooling chamber, all being arranged to cause a circulation of air upwardly through said 95 drying chamber and returning through said cooling chamber. 100

3. A kiln of the class described, comprising a drying chamber, means for supporting articles to be dried in said chamber, heating coils located in said chamber above the articles on said support, an air passage outside of said chamber, an air outlet connecting said drying chamber with said air passage above said heating coils, an air inlet 105 connecting said drying chamber with said air passage below said support, and cooling means adapted to cool the air in said passage and thereby cause a continuous circulation 110 of air through said drying chamber. 115

4. A kiln of the class described, comprising a drying chamber, means for supporting articles to be dried in said chamber, heating coils located in said chamber above the articles on said support, means interposed 120 between said heating coils and the articles on said support and adapted to prevent the radiation of heat from said coils to said articles without interfering with the circulation of air, an air passage outside of said chamber, an air outlet connecting said drying chamber with said air passage above said heating coils, an air inlet connecting said drying chamber with said air passage 125 below said support, and cooling means 130

- adapted to cool the air in said passage and thereby cause a continuous circulation of air through said drying chamber.
5. A kiln of the class described, comprising a drying chamber, means for supporting articles to be dried in said chamber, heating coils located in said chamber above the articles on said support, an air passage outside of said chamber, an air outlet connecting 10 said drying chamber with said air passage above said heating coils, an air inlet connecting said drying chamber with said air passage below said support, cooling means adapted to cool the air in said passage and 15 thereby cause a continuous circulation of air through said drying chamber, said drying chamber, air passage and said air inlet and outlet being substantially co-extensive with each other lengthwise of the kiln.
- 20 6. A kiln of the class described, comprising a drying chamber, means for supporting articles to be dried in said chamber, heating coils located in said chamber above the articles on said support, an air passage outside 25 of said chamber, an air outlet connecting said drying chamber with said air passage above said heating coils, an air inlet connecting said drying chamber with said air passage below said support, cooling means 30 adapted to cool the air in said passage and thereby cause a continuous circulation of air through said drying chamber, and means for charging the air with vapor during its 35 passage between said cooling means and the inlet to said drying chamber.
7. In a kiln, the combination of a storage chamber, means in said storage chamber for supporting the articles which are to be treated, heating means located in said chamber 40 above said supporting means, a cooling chamber extending along one side of said storage chamber throughout substantially the entire length thereof, an air outlet connecting said cooling chamber with said storage chamber above said heating means, an air inlet connecting said cooling chamber with said storage chamber below said support, means for cooling the air in its passage 45 through said cooling chamber.
- 50 8. A kiln of the class described, comprising a room, a vertically disposed partition extending from end to end of said room and subdividing the same into a comparatively wide drying chamber and a comparatively narrow cooling chamber, said chambers being in communication with each other both at the top and bottom of said partition and throughout substantially the entire length of said chambers, heating means in the upper 55 part of said drying chamber, cooling means in the upper part of said cooling chamber, an air outlet in the walls of said room located at a point between said heating and cooling means, and an air inlet opening 60 through the walls of said room at a point

between said cooling means and heating means, and closures for said openings.

9. In a kiln of the class described, the combination of a drying chamber, a cooling chamber in communication with the upper and lower parts of said drying chamber, a support for the articles to be treated in said drying chamber, and two sets of heating means located respectively above and below said support, the upper heating means being spaced above said support to provide space below said upper heating means for the articles to be treated.

10. In a kiln of the class described, the combination of a drying chamber, a cooling chamber in communication with the upper and lower parts of said drying chamber, a support for the articles to be treated in said drying chamber, two sets of heating means located respectively above and below said support, the upper heating means being spaced above said support to provide space below said upper heating means for the articles to be treated, and means for independently controlling the temperature of said 85 two sets of heating means.

11. In a kiln of the class described, the combination of a drying chamber, a cooling chamber in communication with the upper and lower parts of said drying chamber, a support for the articles to be treated in said drying chamber, two sets of heating means located respectively above and below said support, the upper heating means being spaced above said support to provide space 95 below said upper heating means for the articles to be treated, and means for preventing the radiation of heat from said upper heating means to the articles on said support.

12. In a kiln of the class described, the combination of a drying chamber, two sets of heating coils extending horizontally across said drying chamber, being spaced apart vertically to provide a storage space between them for articles to be treated, and being spaced away from the bottom and top of said chamber so as to subdivide the same into three superimposed compartments, a cooling chamber having its upper and lower parts communicating respectively with the upper and lower parts of said drying chamber at points respectively above and below said upper and lower heating coils, and means for separately controlling the temperature of said coils.

13. A kiln of the class described, comprising a pair of superimposed compartments, an air inlet communicating with the lower compartment, an air outlet communicating with the upper compartment, heating means disposed between said compartments, being provided throughout the area of said compartments and being arranged to cause a substantially 125 parts with spaces for the passage of air,

evenly distributed upward flow of air through said compartments, and means adapted to prevent the radiation of heat from said heating means into one of said compartments without disturbing such uniform flow of air.

14. A kiln of the class described, comprising a pair of superimposed compartments, an air inlet communicating with the lower compartment, an air outlet communicating with the upper compartment, heating means disposed between said compartments, being provided throughout the area of said compartments with spaces for the passage of air, and being arranged to cause a substantially evenly distributed upward flow of air through said compartments, and means interposed between said heating means and said air inlet, being co-extensive with said heating means and adapted to prevent the radiation of heat from said heating means into the lower part of said lower compartment, said last named means having air passages therethrough to permit a substan-

tially evenly distributed upward flow of air 25 between said compartments.

15. In a kiln, the construction of a drying compartment, having an air inlet, an air heating compartment above said drying compartment, being co-extensive therewith 30 and communicating therewith throughout its extent, means for heating the air in said heating compartment, and means arranged between said heating means and drying compartment and adapted to intercept substantially all of the heat radiated from said heating means toward said drying compartment, said last named means having air passages therethrough to permit a substantially evenly distributed upward flow of air 35 between said compartments. 40
